(57) **CLAIM**

The ornamental design for a handheld electronic device, as shown and described.

DESCRIPTION

FIG. 1 is a rear elevational view of a handheld electronic device in accordance with our new design;

FIG. 2 is a front elevational view of the handheld electronic device of FIG. 1;

FIG. 3 is a perspective view of the handheld electronic device of FIG. 1;

FIG. 4 is a right side elevational view of the handheld electronic device of FIG. 1;

FIG. 5 is a left side elevational view of the handheld electronic device of FIG. 1;

FIG. 6 is a bottom plan view of the handheld electronic device of FIG. 1; and,

FIG. 7 is top plan view of the handheld electronic device of FIG. 1.

The portions of the handheld electronic device shown in broken lines form no part of the claimed design. The broken line rectangles shown on the rear of the device are unclaimed lines.
